UNITED STATES PATENT OFFICE

ADOLF WELLING, OF KIEL-NEUMUELEN, GERMANY, ASSIGNEE TO FRIED-KRUPP GERMANIAWERFT AKTIENGESELLSCHAFT, OF KIEL-GAARDEN, GERMANY

INTERNAL COMBUSTION ENGINE

Application filed May 17, 1930, Serial No. 453,286, and in Germany May 25, 1929.

The invention relates to multicylinder vertical two stroke cycle internal combustion engines having their scavenging air pump cylinders disposed beside the engine, the pistons of these pump cylinders being actuated from the cross heads of the working cylinders by means of freely projecting rigid arms.

With known engines of this type the scavenging air pumps are disposed beside the working cylinders in such a manner that the axes of one pump cylinder and one working cylinder lie in a common vertical transverse plane, as illustrated in Figures 1 and 2 of the accompanying drawings.

15 The invention has for its object to reduce the width of the upper portion of the engine as it is caused by this known arrangement of the pump cylinders which reduction is desirable more particularly with naval engines 20 with respect to the adjacent gangways and 25 cabins situated about at the level of the cylinders of the engine. According to the invention the scavenging air pumps are arranged in front of and partly within, the gaps existing between two neighboring working cylinders, the drive of two neighboring scavenging pumps being effected from the cross head of the working cylinder situated between these two pumps.

30 It is already known in two stroke cycle engines which have no cross heads to arrange the pump cylinders in front of and between two working cylinders and to drive the pumps from the crank shaft of the engine by 35 a connecting rod or a link fixed on the connecting rods of the two neighboring working cylinders.

In order that the invention can be more readily understood, an embodiment thereof 40 is illustrated by way of example in the drawings in which

Figure 1 is a vertical section on line 1--1 of Figure 2 and shows the older arrangement mentioned above,

45 Figure 2 is a top view thereof,

Figure 3 is a vertical section on line 3--3 of Figure 4 and shows the arrangement of the pump cylinders according to the invention, and

50 Figure 4 is a corresponding top view.

Referring to these drawings, A denotes one of the working cylinders of a multicylinder naval Diesel engine resting on supports B¹, B². The motion of the piston C reciprocating in cylinder A is transmitted by the piston rod D to the cross head E and from there by the connecting rod F to the crank G of the engine shaft. In front and laterally of the working cylinder A is arranged one of the scavenging pump cylinders H the piston K of which is actuated through the intermediary of the piston rod L by an arm P fixed on the cross head E. The scavenging pump is of double action. During the downward stroke air is sucked in from the atmosphere through the suction valves M¹ and during the upward stroke through the suction valves M², the air in the first case entering the compressed air chamber K¹ through pressure valves N¹ and in the latter cases through pressure valves N² from which chamber K¹ it directly passes through the scavenging ports a¹ into the working cylinder. Figures 3 and 4 show clearly the new arrangement of the scavenging air pumps in front of and partly within the gaps existing between the working cylinders A, and their drive from the cross head E by a T-shaped arm P fixed thereon.

As to be seen when comparing the older arrangement illustrated in Figures 1 and 2 with that shown in Figures 3 and 4, the arrangement of the scavenging air pump cylinders according to the invention enables a narrower structure of the upper portion of the engine, see the dotted line on the left in Figures 3 and 4 that indicates the space occupied by the old construction.

The described arrangement of the air pump cylinders on the gaps between the working cylinders affords the further advantage that two scavenging pumps can be driven from one cross head. In this case a notable increase of the bending moment transmitted by arm P to the cross head E does not take place, because arm P is considerably shorter, seen in the vertical plane, Figure 3, than the corresponding arm of the known design, Figure 1.

In lieu of the T-shaped arm P illustrated in Figure 4, two separate arms each extending

from the cross head E can be provided to actuate the two scavenging air pumps.

I claim:-

1. A vertical two stroke cycle internal combustion engine of a plurality of spaced cylinders and associated cross-heads, scavenging air pumps comprising cylinders disposed adjacent to, and partly within the spaces between said spaced cylinders, and means for actuating adjacent scavenging air pumps by the cross-head of the cylinder between them.

2. A vertical two stroke cycle internal combustion engine of a plurality of spaced cylinders and associated cross-heads, scavenging air pumps comprising cylinders disposed adjacent to, and partly within the spaces between said spaced cylinders, and a T-shaped arm connected to the cross-head of a cylinder intermediate two of said pumps adapted to actuate said pumps.

The foregoing specification signed at Hamburg, Germany, this 2nd day of May, 1930.

ADOLF WELLING.
